CLAIM

The ornamental design for a stapler with digital display, as shown and described.

DESCRIPTION

FIG. 1 is a front, right side, top perspective view of the stapler with digital display;

FIG. 2 is a top plan view thereof;

FIG. 3 is a bottom plan view thereof.

FIG. 4 is a right side elevational view thereof, the left side view being a mirror image thereof;

FIG. 5 is a front elevational view thereof;

FIG. 6 is a back elevational view thereof;

FIG. 7 is a front, right side, top perspective view of a second embodiment thereof; and,

FIG. 8 is a left side elevational view thereof, the right side view being a mirror image thereof and all other views being identical to those of the first embodiment.

The broken lines shown in the drawings form no part of the claimed design.
